UNITED STATES PATENT OFFICE

WALTER A. LOOMIS AND SYLVESTER E. BURTON, OF LOS ANGELES, CALIFORNIA

DEEP WELL PUMP AND SYSTEM

Application filed January 26, 1925. Serial No. 4,774.

In its process aspect, our present invention, like that set forth in the separate application S. N. 702,892, filed March 29, 1924, by Walter A. Loomis, patented Sept. 22, 5 1925, No. 1,554,444, one of the applicants herein, may be regarded as relating especially to the recovery of mineral oils, and more particularly to a utilization of relatively light or volatile hydrocarbons, such as "wild" 10 gases from oil wells, in obtaining a large and comparatively regular flow of oil even from wells to which usual methods of production have been found or have become inapplicable.

The mentioned invention of Loomis comprises a mixer insertable at a comparatively low level in a well, to which mixer oil and gas are delivered at substantially the same comparatively high pressure, and in such manner as to form therein an intimate mixture, which increases in frothiness and diminishes in density as it rises, under a combination of forces, to the top of a well; and it is an especial object of our invention to provide means for delivering oil, or gas 20 and oil separately, under the required comparatively high pressure, to a mixer of the general character referred to, or its equivalent.

As indicated, the operation of the mentioned system of Loomis requires a comparatively high pressure upon both gas and oil, or their equivalents, at a mixer near the bottom of a well, or the like; and the objects of our present joint invention include the downward delivery of gas at a higher pressure than that required at the mentioned mixer, and the utilization of the excess energy of this gas, by means such as an engine secured within an oil string, or the like, and directly 30 connected with a pump, in a manner which makes it possible to avoid such an application of high pressures outside said string as might tend to check the inflow of oil to said well.

40 Our present invention relates generally to installations and methods especially suitable for use in the recovery of oil from deep wells; and to a utilization of turbines positioned near the bottoms of such wells and operatively connected with centrifugal pumps

delivering an oil mixture therethrough; and it is an object of this invention to extend the field of usefulness of the methods and principles disclosed in the mentioned application of Loomis, the present invention, in a preferred embodiment thereof, differing from the said prior invention by Loomis in the respect, among others, that a centrifugal pump operated by a pressure and flow of a hydrocarbon gas, or the like, to be mixed with the 55 pumped oil, is used for the purpose of bringing said oil, under a desired upward pressure, to the level of a mixer; and, in the preferred embodiment of our invention herein described, the gas forced downward into 60 a well under high pressure may be, as indicated, utilized as an operating fluid for the driving of a turbine to which the mentioned centrifugal pump is connected; and said gas 65 may then pass to the mentioned mixer, which 70 may be disposed between the said centrifugal pump and said turbine, through which the resultant mixture may rise to a point of delivery.

It is a further object of this invention to 75 provide a turbine engine suitable for use in the general manner above indicated, and capable of numerous somewhat analogous uses.

It is a further object of our invention to provide a system comprising piping, special 80 fittings, packings, connections, and other underground and surface equipment, and also novel methods of operation, suitable for the uses above mentioned.

Other objects and advantages of my invention will be understood from the following description of a preferred embodiment thereof, taken in connection with the appended claims and the accompanying drawings, 85 in which

Fig. 1 is a diagrammatic general view mainly in the form of a vertical section through a well in which an embodiment of our invention is employed (parts being broken away above the level of the usual foot 90 valve, not shown).

Fig. 2 is, for the most part, a vertical half sectional view through a novel turbine engine suitable for use in the practice of our invention, the plane of sectioning being sub- 100

stantially that indicated by the lines 2—2 of Figs. 3 and 8.

Fig. 3 is a horizontal section taken substantially as indicated by the line 3—3 of Fig. 2, with parts broken away.

Fig. 4 is an elevational view, with parts broken away, taken as indicated by the arrow 4 of Fig. 3.

Figs. 5, 6 and 7 are respectively an end 10 elevation, a section, and a front elevation of a preferred type of bucket hereinafter referred to.

Fig. 8 is a horizontal section taken substantially as indicated by the line 8—8 of Fig. 2, 15 with parts broken away.

Fig. 9 is an elevational view taken substantially as indicated by the arrow 9 of Fig. 8.

Fig. 10 is a view taken substantially as indicated by the line 10—10 of Fig. 2, but showing a preferred type of mixer in which the passages for admission of gas are inclined laterally or tangentially as well as upwardly from the exterior.

Fig. 11 is a view of an advantageous type 25 of pump, suitable to be connected by a continuous hollow shaft with an engine, rotors and stators being sectioned on lines 11—11 of Figs. 12 and 13.

Fig. 12 is a horizontal sectional view taken substantially as indicated by the line 12—12 of Fig. 11, showing a rotor only.

Fig. 13 is a similar sectional view of either 30 an intermediate pump stator or a bottom element, this view being taken as indicated by either of the lines 13—13 of Fig. 11.

Referring to the details of that specific embodiment of our invention chosen for purposes of illustration, this embodiment, like 40 that of the mentioned invention of Loomis, may comprise an oil string 11, the lower end of which, or a portion extending through productive strata, may be provided with perforations 12; and within this string we may 45 provide a string of oil delivery tubing 13, the two mentioned strings being connected and secured at the top of the well by means such as a cap 14, shown as provided with lateral pipes 15, 15', respectively valved at 50 16 and 16'.

Within the tubing 13, and at a suitable low level, we may, as in the case of the mentioned invention of Loomis, provide a suitable mixer 17, shown as provided with upwardly and inwardly inclined passages 18 for the admission of gas thereto; and gas on its way to the said mixer, may pass through a gas jacket 19, shown as equal in diameter to and co-axial with the tubing 13 and as extending upwardly from the level of the mixer 17 and provided with inlet ports 20. Although this gas jacket may be regarded as a continuation of the tubing 13, it is shown as rigidly secured, as by a threaded 60 connection and separate screws, to an inter-

mediate fitting 21, which may be provided with a gland 22, to "pack off" a section of inner pipe 23, extending thereabove, and, in the present case, through a packing 24, interposed between the pipe 23 and the tubing 13.

In the mentioned device of Loomis, the mixer 17, or its equivalent, may be entirely stationary; and the same pressure may be applied to the oil on the inside and the outside of a downward extension 25, in open

communication with the interior of the mixer 17; but in our present invention the mixer 17, or its equivalent, may be rotated incidentally to the operation of a pump 26, by which oil

may be delivered at a higher pressure within

said mixer than that which prevails outside

the extension 25,—which, like the jacket 19, with which it may constitute a single main body, may be regarded as a continuation of

the tubing 13. The pump 26 may be any

usual or preferred type of centrifugal pump,

and it may comprise stators 27, rigidly secured, as by means of screws 28, within the

extension 25. To impart rotation to the

rotors 29 of such a centrifugal pump, assuming such rotors to be rigidly connected in a

usual manner with a central shaft section 30,

or its equivalent, we may connect the same by

any suitable means, as by a spider 31 having

apertures 32, with a hollow shaft section 33,

with which the mixer 17, or its equivalent,

may be integral; and rotation may be im-

parted to this sectional shaft by means such

as a special turbine 34, adapted to fit within

the jacket 19, comprised in the mentioned

main body, assuming this to be a stationary

element.

In the disclosed embodiment of the turbine

34, the hollow shaft section 33 is shown as

extending from the rotatable spider 31

through the stationary gland 22, in which it

may freely rotate while delivering the

pumped oil to the mentioned pipe 23, shown

as threaded into an extension 35 projecting

upwardly from said gland; and on the hollow

shaft section 33, or its equivalent, we may

- ing bodies or discs 38, provided with buckets inclined oppositely to those of the discs 36, and surrounded and rigidly retained by the bands 40,—which may be of sufficient breadth to extend also past spacing rings 43. It will be understood that sets of turbine elements corresponding in function to the above may be duplicated to any necessary or desired extent, three sets of such elements being illustrated in Fig. 2. All of the mentioned rotor elements and the spacers 43 are shown as threaded onto the hollow shaft section 33; and the shaft comprising the mentioned sections may be provided with, for example, a bearing sleeve 44, shown as secured by screws 45 in addition to threads 46. Thrust ball bearings may optionally be provided both at 47 and at 48, whether or not arrangements be made for balancing effects, as hereinafter proposed.
- The upper ball bearing 47 may be a double-thrust bearing secured above a nozzle and comprising a channeled two-part seat 49, 49'; and the lower bearing 48, when provided, may be retained between, for example, a shoulder 50 and a fixed bearing sleeve 51, or the like, the latter being a guide provided with a lining 52 of a bearing metal or alloy and retained by means including screws 53 and a ring or shoulder 54, projecting inwardly from the extension 25.
- When the mentioned parts are of sufficient rigidity and durability, assuming the rotors of the engine 34 and the pump 26 to be permanently secured in co-axial alignment, it may be regarded as unnecessary to provide, as at 55, Fig. 1, an additional bearing spider to receive end thrust; and it will be understood that such end thrust may be substantially eliminated by suitable expedients of design and operation.
- So far as an efficient action of the mixer 17 is concerned, the rotation of this element may be regarded as of minor importance or wholly incidental to the transmission of power from the turbine 34 to the pump 26; but since apertures 18 are designed for the inward admission of gas, it may be regarded as desirable that these apertures be given such a lateral or spiral inclination as may contribute to the inward movement of the gas therethrough; and we consider it advantageous to so form, for example, the mentioned spider 31, or its equivalent, as to constitute the same an impeller tending to force oil, or the like, into the hollow shaft section 33, or its equivalent, and upwardly therethrough. This element obviously then becomes, in a sense, a supplement to or a part of the pump 26, whether or not any plates are provided interiorly of said shaft; and in order wholly or partially to counterbalance or offset the downward thrust of the rotor elements of the engine 34, when designed along the lines indicated, we may so form any rotat-
- tating spider 31, serving as an impeller, and we may utilize in the pump 26, or its equivalent, runners or rotors so designed, that the upward thrust produced by the reaction thereof against the pumped oil may, to any suitable extent, oppose the mentioned downward thrust of the engine 34.
- It will be noted that the intermediate fitting 21 and the gland 22 are held stationary, (the former being shown as secured by threaded connections, and also by screws 56, to the tubing 13, or a continuation thereof, and the latter being shown as retained in its adjusted position by bolts 57) while the hollow shaft section 33, delivering to the pipe 23 the pumped oil or other fluid in admixture with gas, rotates therein; and any desired inserts 58, of a bearing metal, or the like, may accordingly be provided in either or both of these elements. To avoid undue wear of parts, any usual or preferred means may be employed to prevent entrance of sand, or the like, into the downward extension 25 of the tubing string 13, which extension preferably reaches to or near the bottom of a well and may be provided with sand-excluding apertures (not shown in Fig. 1) at any desired level below pump 26, or its equivalent; and an outer casing C may be cemented off at a suitable level, as at C'.
- Although there may be certain cases in which gas naturally occurring in a well can be directly utilized for pumping, as by an admission of the same through lateral openings 20a shown as closed by plugs 20b, which are capable of being transferred at will to the correspondingly threaded apertures 20c at the upper ends of the gas passages 20, gas from any suitable source may be delivered into the oil string 11, or its equivalent, and transferred therefrom to the interior of the tubing 13, or its equivalent, at any suitable level lower than that of the mentioned packing 24. For example, an additional packing 59 may be inserted at a suitable level below the packing 24; and lateral apertures 60 or equivalent communicating means, may permit gas under high pressure to be delivered downwardly, and substantially as indicated by arrows 61, simultaneously with an advance of oil somewhat as indicated by arrows 62, the consequent advance of an oil and gas mixture being substantially as indicated by arrows 63. The oil and gas mixture, or other mixture, delivered at the top of the well, may be separated in any suitable way, as by means of over-size separators S; and compressor C, or its equivalent, may be employed to force all or a portion of the gas back into the same or another well, as through pipe 62a. Separated oil, or a desired product, may be withdrawn, as through a pipe 63a, for purification, use, storage or sale.
- Unavoidable leakages, the condensation of liquid hydrocarbons from the gas forced in-

to a well, and successful balancing of thrusts may largely or entirely obviate the necessity for special structures or provisions directed to an effective lubrication of our turbine engine; but, if desired, any suitable quantity of a preferred lubricating oil may be delivered to our turbine, without introducing any additional pipes in a well, by means such as an auxiliary tank L, from which a valved branch 64 is shown as extending to the pipe 62a, through which gas may be forced into the well; and separate apertures 65 may be provided, if desired, at any suitable low level, to facilitate the advance of a lubricant admitted, in the manner described, or in any equivalent manner, through tubing 13. Within this tubing it may freely advance to the bearings of the turbine 34, any sand contained in the lubricant being separated, as at 65a.

As suggested in Figs. 10-13 inc., instead of using a sectional shaft of which only a part is hollow, and instead of admitting oil below the pump 26, we may employ a one piece hollow shaft 33' extending continuously, and with or without a change in diameter, downward from engine 34, or its equivalent, through both a mixer and a pump 27a; and oil may be admitted to this pump through the extension 25' at any suitable levels, such as those of the openings 65', above said pump 27a.

In this form of our invention, the pump stators 66 being shown as secured to the extension 25', and the pump rotors or runners 67 being rigidly secured to a slightly constricted lower portion 68 of the hollow shaft 33', these elements may be proportioned somewhat as shown; and a bull plug 69 serving as a transverse partition across the extension 25' below the end of the shaft 33' and optionally provided with a central depression, may serve to secure not only a special bottom stator 70, below the lowermost of the rotors or runners 67, but also in case spacers 71 are employed, to prevent longitudinal movement of the entire set of stators, although the latter are shown as separately secured by screws 72.

By devices of the general character above suggested, the opposite thrusts upon the shaft 33', or its equivalent, may be balanced with any required degree of precision. By making the diameter of the shaft 33' less in the region of the pump than in the region of the engine, we moreover provide adequate space for the rotors of the pump, and we also provide for such an increase in the capacity of the shaft 33' as shall enable it to take care of the increased volume resulting from the admission of gas through the mixer 17, without any immediate or notable increase in the upward velocity of the mixture through the interior of the engine, as compared with the

upward velocity of the pumped oil through the interior of the pump.

Although exact pressures and dimensions may be regarded as immaterial to our present invention, assuming, by way of illustration, that (1) our pumping organization is installed at so low a level that the hollow shaft section 33 and the pipe 23 can have a diameter of only about $1\frac{1}{2}$ inches, the associated engine parts being proportioned substantially as indicated in Fig. 2, and assuming (2) that the oil level in an oil string during production is such as to provide an upward pressure of some 50 pounds, at the level of the mixer 17 and in addition to that due to pumping, and assuming (3) that a pressure of about 250 pounds is desired at the mixer, then gas may be supplied to the uppermost stage of the turbine 34, or its equivalent, at a pressure such as 350 pounds, and the pump 26, or its equivalent, may be so constructed or adjusted as to produce, on pumped oil of a particular type, an additional upward pressure of some 200 pounds, so that both the oil and the gas may reach the mixer at substantially the same pressure of 250 pounds,—the drop of 100 pounds in pressure, during the passage of the gas through the turbine, representing energy used in operating the pump, or lost as heat, or the like. In this illustration it is of course assumed that the mentioned pressure of 250 pounds at the mixer is a pressure ascertained to be suitable, in the case of a particular well, to deliver a desired mixture, increasing in frothiness as it rises, at a desired rate, to the top or beyond the top of a well; but it will be obvious that the principle of our invention is not restricted to the use of any particular operating fluid, nor to the pumping of any specified liquid.

Although we have herein described alternative complete embodiments of our invention, it will be understood that various features thereof might be independently employed, also that various modifications might be made by those skilled in the art to which this case relates, without the slightest departure from the spirit and scope of our invention, as the same is indicated above and in the following claims.

For example, depending upon its availability in the elevation of a particular liquid pumped, we may optionally introduce CO_2 , or exhaust gases containing the same, into the pipe 62a, to serve as an operating and elevating fluid; and whenever the operating fluid employed is such as to form a deposit on the rotor blades of our engine, or elsewhere, we may optionally introduce at suitable intervals, either in conjunction with a lubricant or separately therefrom, a solvent substance such as an alkaline reagent adapted to cut and remove the mentioned deposits. We suggest the use of a soft soap

containing free alkali as suitable for a combined lubricating and solvent effect when separated hydrocarbon gases are used substantially as above described.

We claim as our invention:

5. 1. An organization of the character described which includes an engine, a pump therebelow, a stationary tubing extending above said engine, a packer carrying said tubing, a pipe extending within said tubing and to a point above said packer, and a vertical hollow shaft between said engine and said pump, and in which said engine and said pump both include stationary elements secured to said stationary tubing and said vertical hollow shaft constitutes means for delivering a pumped liquid into said pipe.

10. 2. An organization of the character defined in claim 1 which includes an oil string and also an additional packer interposed between said tubing and said oil string, and in which means are provided whereby an operating fluid, in its descent to said engine, is transferred from said oil string to said tubing at a level between the first mentioned packer and said additional packer.

15. 3. In an organization of the character described, a centrifugal pump, and a turbine engine producing an exhaust gas and directly connected with said pump by a vertical shaft, the said shaft being hollow, inlets communicating with the interior of said shaft to permit the advance of pumped liquid and commingled exhaust gas therethrough, said inlets being adapted to serve as a mixer for said pumped liquid and said exhaust gas.

20. 4. In an organization of the character described, a delivery tubing, a centrifugal pump and a turbine engine producing an exhaust gas and directly connected with said pump by means of a hollow shaft adapted to permit upward advance of pumped liquid and commingled turbine exhaust gas, rotors on said shaft, said hollow shaft being provided with gas inlets, to provide turbine exhaust gas ports and to serve as a means to commingle pumped liquid fluid and exhaust gas.

25. 5. In an organization of the character described, a pump, a turbine producing exhaust gases and connected with said pump by means comprising a hollow shaft for the reception of pumped liquid, and a mixer in said shaft for the admission of exhaust gases from said turbine.

30. 6. In an organization of the class described, a pump, a turbine adapted to deliver exhaust gas and connected with said pump by means of a laterally apertured hollow shaft extending through said turbine and providing an exhaust conduit for a pumped mixture including said exhaust gas, said laterally apertured hollow shaft permitting the exhaust gas to enter said hollow shaft to commingle with the pumped fluid.

7. In an organization of the character described, a pump, a turbine producing exhaust gases and connected with said pump by means of a laterally apertured hollow shaft to which both the pumped liquid and the gases exhausted from said engine are admitted for evacuation, said lateral apertures being adapted to permit the exhaust gases to flow into the interior of said hollow shaft.

10. 8. In an organization of the character described, a pump, a turbine adapted to deliver exhaust gases within a well and connected with said pump by means comprising a hollow shaft adapted to receive said gases and also the pumped liquid, and means comprising a concentric tubing outside of and extending above said shaft, for delivering a lubricant and gas to said turbine.

15. 9. A turbine engine, a mixer and a centrifugal pump disposed on a substantially vertical axis, the fluids from said engine and pump passing through said mixer, said engine and pump being provided with rotor blades on a common shaft and adapted to produce a substantial balance of end thrusts.

20. 10. A turbine engine and a centrifugal pump disposed on a substantially vertical axis and provided with rotor blades on a common shaft and adapted to produce a substantial balance of end thrusts, a passage for the pumped liquid admitted with exhaust gases being provided through said turbine.

25. 11. In an organization of the class described, an oil delivery tube, a pump in said oil delivery tube, a turbine in said oil delivery tube, a coupling operatively joining said pump and said motor, a hollow shaft extending through said turbine, stators secured to the enclosing wall of said turbine pump, rotors mounted on said hollow shaft, said shaft extending below said turbine and being provided with an opening for the advancement of commingled fluid and gas therethrough.

30. 12. In an organization of the class described, an oil delivery tube, a pump in said oil delivery tube, a turbine in said oil delivery tube, a coupling operatively joining said pump and said motor, a hollow shaft extending through said turbine, stators secured to the enclosing wall of said turbine, pump rotors mounted on said hollow shaft, said shaft extending below said turbine and being provided with openings for commingled fluid and gas therethrough, and a mixer included within said hollow shaft at a point below the turbine, said mixer serving as means through which exhausted gases are admitted to said shaft.

35. 13. In an organization of the character described, a hollow shaft, a mixer formed as part thereof and through which fluids may pass into the shaft, means for delivering oil upwardly to the interior thereof, means for delivering gas laterally thereto by passages upwardly and laterally inclined, said oil de-

livery means including a rotatable portion of
said hollow shaft and the mixer carried
thereby.

In testimony whereof, we have hereunto set
5 our hands at Los Angeles, California, this
15th day of January, 1925.

WALTER A. LOOMIS.
SYLVESTER E. BURTON.
